UNITED STATES PATENT OFFICE.

MAXIMILIAN A. WINTRICH, OF CHICAGO, ILLINOIS.

DRUM.

1,290,823.

Specification of Letters Patent.

Patented Jan. 7, 1919.

Application filed June 22, 1918. Serial No. 241,332.

To all whom it may concern:

Be it known that I, MAXIMILIAN A. WINTRICH, a citizen of the United States, and a resident of Chicago, in the county of Cook and State of Illinois, have invented new and useful Improvements in Drums, of which the following is a specification.

My invention relates to drums, particularly to improved tension adjusting mechanism for the heads thereof.

For the best results in tone vibration and other qualities there should be relative adjustment of the tensions of the batter head and the snare head in order that the snare head can properly respond to the vibrations of the batter head. In prior arrangements provision is made for independent adjustment of the heads but such independent adjustment can be accomplished only in a laborious manner. For example in Patent No. 1,254,756 issued January 29th, 1918, to T. Wilson, independent adjustment can be made to obtain different relative tensions in the heads but such adjusting operation requires the turning to different degrees of the setting stems connected with the respective hoops and the operation is therefore laborious and uncertain.

One important object of my invention is to provide improved means for simplifying and making more certain the relative adjustment of the drum heads. To get the best results the tension of the batter head should be greater than that of the snare head, that is, the batter head should be more taut and the snare head should be more free to respond to the vibrations of the batter head. To accomplish this I provide a plurality of tension adjusting units for the drum, each of which units has a greater number of contacts with the batter head hoop than with the snare head hoop, the increased number of contacts on the batter side hoop causing more equal distribution of the transverse adjusting pull on the hoop and consequently increased tightening of the batter head, the spaces of the hoop between contacts being so short that the hoop must at all points follow the pull of the adjusting units. I have found that adjusting units properly spaced

and having each two engagements with the batter side hoop for one engagement with the snare side hoop give very efficient results. With such arrangement the proper relative tension of the heads can be automatically accomplished by turning each setting stem the same distance.

On the accompanying drawing I show a construction and arrangement which embody the above and other features of my invention. On the drawing

Fig. 1 is a side elevational view of a drum,

Fig. 2 is an enlarged front elevational view of one of the adjusting units with parts thereof in section,

Fig. 3 is a sectional view on plane 3-3, Fig. 2, and

Fig. 4 is an interior view of a section of the drum showing the manner of connecting the units thereto.

On the drawing, 10 represents the cylindrical drum shell over whose edges the batter head 11 and snare head 12 are stretched to be held in place by their respective hoops 13 and 14 with which the tensioning mechanism engages. Each tensioning unit comprises a horizontal bar or yoke 15 having the studs 16 and 17 extending inwardly from its ends to be secured against the outer face 80 of the shell in a preferred manner to be described later. At the center of the bar 15 is the conical pocket 18 for receiving the conical head 19 of a sleeve or tube 20 which is internally threaded for the reception of an 85 adjusting stem 21. The adjusting stem extends through the opening 22 in the lug 23, which lug is on the plate 24 whose outer end 25 engages around the outer edge of the snare head 14. On the stem 21 is a collar 26 90 which abuts against the outer face of the lug 23, and the outer end 27 of the stem is polygonal for the reception of a socket key. Through the ends of the bar 15 are the conical pockets 28 and 29 respectively for receiving the conical heads 30 and 31 of the internally threaded tubes 32 and 33. In these tubes the adjusting stems 34 and 35, respectively, engage, these stems extending through the lugs 36 and 37 on the plates 38 100

and 39 which hook over the outer edge of the batter head hoop 13. These stems have collars 40 and 41, respectively, and the polygonal key receiving ends 42 and 43. To prevent turning of the threaded sleeves when the stems are turned, their conical heads are preferably knurled or toothed and the receiving pockets in the bar 15 are correspondingly knurled or toothed. Such arrangement permits the tubes to be readily withdrawn and will hold them rigidly against turning when they are inserted in the pockets during the adjusting operation.

Each unit has thus one connection with the snare side hoop and two connections with the batter side hoop, and the units are so spaced around the drum and the length of the bars 15 is such that the spaces of the hoop 13 between the points of engagement of the adjusting units are sufficiently short to prevent any material transverse give or distortion of the hoop so that the adjusting pull on this hoop will be practically uniform, which results in uniform distribution of tension on the batter head. On the snare side of the drum where there are only one-half as many adjusting contacts the section of the hoop between the contacts are more free to give and the tension on the snare head will not be so uniform. When the drum is first adjusted the stems for both sides are turned the proper distances to produce the proper relative tension in the heads; the adjustment of the batter head being such that it will give the proper vibration when struck, and the relative adjustment of the snare head being such that this head can most efficiently respond to the vibrations of the batter head. After such first adjustment or setting of the drum slight future adjustment, which will be necessary on account of weather or atmosphere changes, can be very easily made by turning each stem the same distance, such equal turning resulting automatically in maintenance of the proper relative tension of the heads. This, of course, is a very simple and efficient procedure as the drummer need only turn each stem the same distance.

In drums where the shell and hoops are of metal it is desirable to eliminate metallic contact between the adjusting units and the shell in order to eliminate as much as possible any metallic ringing noise when the drum is played. A preferred connection between the bars 15 and the drum shell is shown in Figs. 3 and 4, where washers 44 and 45 of deadening material, such as fiber, are inserted between the studs on the bars and the heads of screws 46 which extend through enlarged openings 47 in the shell; these screws preferably extending from the inside of the drum through these openings and into the studs, the drum shell being then securely clamped between the fiber

washers and preventing any metallic contact with the shell of the studs and screws. The bars 15 by being secured at their ends to the drum shell will assist in keeping the shell of cylindrical form and will prevent distortion thereof during the adjusting operation.

Instead of having, as shown, two contacts with the batter side hoop to one contact with the snare side hoop, the ratio of contacts for each unit may be different. Other changes and modifications may also be made without departing from the scope of the invention.

I claim as follows:

1. In a drum, the combination with the shell, the batter and snare heads, and the hoops, of tensioning units arranged around the shell, each unit comprising a support anchored to the shell and longitudinally adjustable arms extending therefrom into engagement with the hoops, each unit having more arms in engagement with the batter head hoop than with the snare head hoop.

2. In a drum, the combination with the shell, the batter and snare heads, and the hoops, of tension adjusting units spaced around the shell, each unit comprising a bar anchored to said shell and adjustable tension connections between the bar and the hoops, there being a greater number of such connections to the batter head hoop than to the snare head hoop.

3. In a drum, the combination with the shell, the batter and snare heads, and the tension hoops, of tensioning units anchored to said shell and having connection at their outer ends with the hoops, there being a greater number of units for the batter head hoop than for the snare head hoop.

4. In a drum, the combination with the shell, the batter and snare heads, and the hoops, of a plurality of tensioning units spaced around the shell, each unit comprising a bar anchored to the shell, longitudinally adjustable arms extending from the ends of said bar into engagement with the batter side hoop and one arm extending from an intermediate part of the bar and into engagement with the snare side hoop.

5. In a drum, the combination with the shell, the batter and snare heads, and the hoops, of tensioning mechanism comprising a bar anchored to the shell, said bar having a conical pocket, an internally threaded sleeve having a conical head engaging in said pocket, a stem threading in said sleeve and anchored to one of said hoops, said stem being rotatable and forming a longitudinally adjustable structure with said sleeve by virtue of its threaded engagement therewith, said pocket and conical head being knurled whereby rotation of said sleeve is prevented when said stem is turned.

6. In a drum, the combination with the shell, the batter and snare heads, and the

hoops, of tensioning mechanism comprising a bar anchored to the shell, a longitudinally adjustable tensioning arm comprising two links threaded together, said bar having a 5 conical pocket and one of said links having a conical head engaging in said pocket, said pocket and head being knurled to prevent

turning of said link in said pocket, said other link being rotatable and anchored to one of said hoops.

10

In witness whereof, I hereunto subscribe my name this 20th day of June, A. D., 1918.

MAXIMILIAN A. WINTRICH.
